UNITED STATES PATENT OFFICE

GEORGE P. WIGGINTON, OF KALAMAZOO, MICHIGAN, ASSIGNOR, BY MESNE ASSIGNMENTS, TO REMINGTON RAND INC., OF NEW YORK, N. Y., A CORPORATION OF DELAWARE

TEMPORARY BINDER

Application filed August 15, 1924. Serial No. 732,216.

This invention relates to improvements in temporary binders.

The main object of this invention is to provide an improved temporary binder which is well adapted for holding loose sheets, circulars and the like and one in which the binding mechanism is very compact thereby making it well adapted to binders of small dimensions having flexible covers.

10 A further object is to provide a binder having these advantages which may be readily opened at any desired place for the removal or insertion of sheets and readily reassembled.

15 Objects pertaining to details and economies of my improvements will readily appear from the detailed description to follow.

I accomplish the objects of my invention by the devices and means described in the 20 following specification. The invention is clearly defined and pointed out in the claims.

A structure which is a preferred embodiment of my invention is clearly illustrated in the accompanying drawing forming a part 25 of this application, in which:

Fig. I is a plan view of a structure embodying the features of my invention with the top cover thrown back, or open.

Fig. II is a perspective view of the covers 30 of the binder open with the sheets and the transfer bar removed.

Fig. III is an enlarged detail section on a line corresponding to line 3—3 of Figs. I and IV.

35 Fig. IV is a detail longitudinal section on a line corresponding to line 4—4 of Figs. I and III.

Fig. V is a fragmentary perspective view 40 of the sheets removed from the binder with the transfer bar.

Fig. VI is an inverted perspective view of the transfer bar.

In the drawing the sectional views are 45 taken looking in the direction of the little arrows at the ends of the section lines and similar numerals of reference indicate similar parts in all of the views.

Referring to the drawing, the covers 1, 1 50 are, in the embodiment of my invention illustrated, flexible covers and they are con-

nected by a flexible back 2. The binding flaps 3 and 4 are connected to the covers by the flexible hinge connections 5.

I provide a bottom binding bar 6 having 55 posts 7 mounted thereon, this bottom binding bar being connected to the bottom binding flap 3 by means of the fasteners 8. These fasteners are preferably flexible fasteners so that the binding bar may be readily assembled with or detached from the binding 60 flap as desired.

The top binding bar 9 is connected to the top binding flap by means of fasteners 8. These binding bars may, however, be permanently connected to the binding flaps if 65 desired.

The top binding flap and top binding bar have holes 10 therein adapted to receive the binding posts 7. These binding posts have 70 opposed slots in their ends providing heads 11 with reduced neck portions 12 which project through the top binding bar as shown in Figs. III and IV. A locking slide 13 is mounted upon the top binding bar, this locking slide being provided with key-hole slots 75 14 adapted to engage the heads of the posts. The locking slide has longitudinal slots 15 therein engaging the headed studs 16 whereby the slide is slidably supported.

I provide a transfer bar 17 having holes 80 18 therein adapted to receive the binding posts so that this transfer bar may be arranged on the inner side of the top binding bar. The transfer bar is provided with posts 19 adapted to engage holes 20 in the sheets 85 21, the sheets also having holes 22 for the binding posts.

In use the sheets are arranged upon the posts 7, the transfer bar engaged with the sheets, the top binding bar closed and the 90 binder locked by means of the locking slide. When it is desired to open the binder for insertion or removal of sheets, the top binding bar is released and disengaged from the posts and the sheet body can be opened at the desired place by lifting off the sheets above that point together with the transfer bar, the transfer bar holding the sheets in proper alignment so that they may be replaced as a body as indicated in Fig. V, or, of 95 100

course, the entire sheet body may be arranged on the transfer bar and then replaced in the binder, or manipulated as desired.

My improvements are especially designed by me for embodiment in relatively small binders, although desirable and readily adapted for use in larger binders.

Having thus described my invention what I claim as new and desire to secure by Letters Patent is:

- 10 1. In a temporary binder, the combination of covers, binding flaps on the covers, binding bars detachably connected to said flaps, binding posts on one of said bars, means on the other bar for locking the ends of the binding posts thereto, and a transfer bar provided with sheet-engaging posts removably disposed inwardly of the last-mentioned binding bar.
- 20 2. In a temporary binder, the combination of covers connected by a flexible back, binding flaps on the covers, top and bottom binding bars detachably connected to said flaps, binding posts on one of said bars engageable in openings in the other bar, means for detachably locking said posts in said openings, and a transfer bar provided with sheet-engaging posts removably disposed inwardly of the binding bar having the post-receiving openings.
- 30 3. In a temporary binder, the combination of covers connected by a flexible back, binding flaps hinged on the covers, top and bottom binding bars detachably connected to said flaps, binding posts on the bottom binding bar engageable in openings in the top binding bar, means on the top bar for detachably engaging and locking the ends of said posts in said openings, and a transfer bar provided with sheet engaging posts and having openings to slidably receive said binding posts removably disposed inwardly of the top binding bar.

In witness whereof I have hereunto set my hand.

GEORGE P. WIGGINTON.
